WINDOW LATCH HANDLE

Andrew J. Campbell, Bloomfield Hills, Mich., assignor to
Al-Craft Manufacturing Company, Troy, Mich., a cor-
poration of Michigan

Filed Jan. 9, 1969, Ser. No. 15,284

Term of patent 14 years

Int. Cl. D8—03

U.S. Cl. D8—111

FIGURE 1 is a top plan view of a window latch handle embodying my new design, showing the same mounted on a base.

FIGURE 2 is a bottom plan view of the window latch handle.

FIGURE 3 is a side elevational view of the window latch handle, shown mounted on the base.

FIGURE 4 is a view in end elevation of the window latch handle.

FIGURE 5 is a further end elevational view but from the opposite end of the window latch handle.

The dominant features of the design reside in the portions shown by means of full lines, the dot-dash showing of a mounting base for the window latch handle being for illustrative purposes only.

I claim:

The ornamental design for a window latch handle, substantially as shown and described.
